UNITED STATES PATENT OFFICE.

FRANK CARTER AND EVERSHED CARTER, OF STAMFORD, ENGLAND, ASSIGNEES OF
ONE-THIRD TO EDWARD CHRISTOPHER BLACKSTONE, OF STAMFORD, ENGLAND.

INTERNAL-COMBUSTION ENGINE.

942,886.

Specification of Letters Patent. Patented Dec. 14, 1909.

Application filed March 8, 1909. Serial No. 481,676.

To all whom it may concern:

Be it known that we, FRANK CARTER and EVERSHED CARTER, both subjects of the King of Great Britain, residing at Rutland Iron Works, Stamford, Lincolnshire, England, have invented new and useful Improvements in Internal-Combustion Engines, of which the following is a specification.

Our invention relates to internal combustion engines, more particularly adapted for burning crude oil or other heavy fuel, which is injected or sprayed into the combustion chamber at or near the end of the compression stroke, and wherein the compression is comparatively low, *i. e.*, not sufficiently high to effect ignition of itself; the object of our invention being to provide improved means for igniting the charges with equal certainty whether such engines are run with no load or with a light load or with a full load.

According to our invention we provide for delivering into a separate combustion chamber, joined by a port to the main combustion chamber, and hereinafter called the igniter (which is heated preferably by a lamp at starting) an auxiliary charge or spray at predetermined intervals, whereby a comparatively even temperature will be maintained in the said igniter, and we provide for causing the flame resulting from the explosion of this auxiliary charge to impinge against the spray of fuel for the main charge so that when a charge is admitted into the main combustion chamber, the flame from the explosion in the igniter will fire the main charge, the supply of fuel for which is controlled by the governor.

In a suitable arrangement for carrying out our invention the valves and nozzles for the main and auxiliary sprays are arranged in a box hereinafter referred to as the "spray box" attached to the end of the main combustion chamber, and the igniter is fixed beside such a box at a suitable angle to receive the auxiliary spray and project the flame of combustion into the path of the main spray as the latter is injected into the main combustion chamber.

To enable our invention to be fully understood, we will describe the same by reference to the accompanying drawings, in which—

Figure 1 is an end view of a portion of an internal combustion engine provided with our improvement. Fig. 2 is a sectional plan on the line 2—2, Fig. 1, and

drawn to a larger scale than Fig. 1, and, Fig. 3 is a section on the line 3—3, Fig. 2. Fig. 4 is a plan of part of the mechanism shown in Fig. 1.

a is the main combustion chamber of the engine cylinder, *c* the air inlet valve, and *d* the exhaust valve, the said valves being operated in the ordinary manner from the half speed shaft *e*.

f is the spray box which is attached to the end of the combustion chamber *a*, and which, as shown, has a chamber or jacket *f'* through which water is caused to circulate, for cooling purposes, formed upon it. This spray box is provided with a nozzle *f''*, through which the main charge of oil supplied by the pump *g* through the pipe *g'* is sprayed into the combustion chamber *a*; the said nozzle having arranged in conjunction with it the valve *h* which extends through an oil reservoir *h'* formed around it, and at its rear end is supported in a guide bracket *h''*, Fig. 4, on the cylinder cover; this valve *h* is normally held upon its seat by means of a spring *h''*, which at one end bears against the bracket *h''*, and at the other end against a stop collar *h'''* on the stem. This valve is operated to open the nozzle *f''* by a cam *i* on the half speed shaft *e*, the motion of the said cam being transmitted to the valve *h* through the medium of the rod *j*, carried at one end upon a pivoted lever *j'*, and at the other end sliding in a hole in a bracket *j''* on the cylinder cover. On the rod *j* there is a tappet *j'''* which co-operates with an arm *k* on the lower end of a spindle *k'* which rocks in a socket in the bracket *j''*, and at its upper end carries another arm *k''*, the forked end of which engages behind the collar *h'''* so that each time the rod *j* is moved longitudinally by the cam *i*, the said valve *h* will be moved from its seat so that the oil in the reservoir *h'* will be ejected by compressed air entering through the pipe *h''* and subsequently be returned to its seat by the spring *h''*.

l is the igniter which is fixed to the end of the combustion chamber *a* and which is connected with the interior of the latter by a port *l'*, which is inclined so that it converges toward the line of discharge of the nozzle *f''*.

Attached to the spray box *f* is the nozzle *m* for the auxiliary spray, which nozzle communicates at its rear end with the reservoir *h'* around the valve stem *h* but at a some- 110

what higher level as shown clearly in Fig. 3. This nozzle *m* is controlled by a valve *n* the stem of which at its rear end slides in a bracket *n'* and carries a collar *n''*, between which, and the bracket *n'*, a spring *n³*, which serves to hold the valve *n* upon its seat, is arranged similarly to the spring *h³* hereinbefore described in connection with the valve *h*. This valve *n* is also operated to open it, by a tappet *o* on the rod *j*, the tappet acting against one end of a lever *o'* pivoted upon the cylinder cover, the other end of which lever is forked and bears against the collar *n''*.

15 Into the igniter *l* a rod *p* of refractory material which will readily retain the heat is introduced, and on the nozzle *m* is provided a lip *p'* which serves to divert the spray issuing from the nozzle on to the said rod. The pipe *g'* through which the liquid fuel is delivered by the pump *g* is connected to an annular port *q* around the nozzle *m*, and which communicates with a space *q'* around the valve *n* through a series of holes *q''*, so that the oil delivered by the pump into the reservoir *h'* passes through the space *q'*, this space being so small that capillary attraction will retain the latter full of oil, the surplus passing into the reservoir *h'* for the main charge. When the engine is running light the throw of the pump *g* is such that practically only sufficient oil will be delivered at each stroke to fill the space *q'*, the quantity of oil delivered by the pump being increased as the load increases, the surplus passing into the reservoir *h'*. As shown in the drawing, this regulation of the throw of the pump is effected in the following manner, that is to say, the plunger of the pump *g* is operated by a bell-crank lever *r* connected at one end to a crank pin *r'* on the half speed shaft *e* and at the other end moving in a slot *r''* in the said plunger. Into this slot also depends a wedge *s* which is raised or lowered by means of the governor *t* in such a manner that under a heavy load the consequent decrease of speed causes the thick end of the wedge to be lowered into the slot and under a light load the thin end, the extent of the movement imparted to the plunger being increased or diminished accordingly.

20 The operation of the apparatus hereinbefore described is as follows, that is to say, at or near the end of the compression stroke the spraying valves *h*, *n* are opened so that the main spray will be delivered into the combustion chamber *a* through the nozzle *f'* and the auxiliary spray into the igniter *l* through the nozzle *m*. In the igniter *l* the spray will be ignited and the flame produced by combustion will be projected through the port *l'* and ignite the main charge in the combustion chamber. If, as before indicated, the engine is running light so that little or no oil is delivered in the main reservoir

25 *h'*, the spray will nevertheless be injected at each cycle into the igniter *l* so that the latter will be maintained at a practically uniform temperature notwithstanding that for several cycles no charge is introduced into the main combustion chamber.

30 *u* is a plate which we preferably employ attached to the piston (not shown) of the engine and serving to deflect the spray issuing from the nozzle *f'*.

35 Instead of arranging both spraying devices in connection with a single spray box, each spraying device may be upon an independent spraying box, and in this case a separate pump is provided for each spraying device.

40 Although we have shown our invention as applied to an engine of the horizontal type, it is to be understood that our improvements are equally applicable to vertical engines.

45 Having now particularly described and ascertained the nature of our said invention and in what manner the same is to be performed, we declare that what we claim is:—

1. In an internal combustion engine, the combination with the explosion chamber, and a separate ignition chamber having a flame delivery passage communicating with the explosion chamber, of fuel supplying means provided with separate passages communicating with the explosion chamber and the ignition chamber, and means for independently controlling said separate passages.

50 2. In an internal combustion engine, the combination with the explosion chamber, and a separate ignition chamber having a flame delivery passage communicating with the explosion chamber, of fuel supplying means provided with separate passages communicating with the explosion chamber and the ignition chamber, and means for throttling the fuel supply to the explosion chamber without affecting the supply of fuel to the ignition chamber.

55 3. In an internal combustion engine, the combination with the explosion chamber, and a separate ignition chamber having a flame delivery passage communicating with the explosion chamber, of fuel supplying means provided with separate passages communicating with the explosion chamber and the ignition chamber, and governor controlled mechanism for throttling the supply of fuel to the explosion chamber without affecting the supply of fuel to the ignition chamber.

60 4. In an internal combustion engine, the combination with the explosion chamber, and a separate ignition chamber, having a flame delivery passage communicating with the explosion chamber, of fuel supplying means provided with separate passages communicating with the explosion chamber and the ignition chamber, and provided with a reservoir in communication with said sep-

arate passages, separate valves controlling said fuel supply passages, and a governor for controlling the fuel supply to said reservoir.

5. In an internal combustion engine, the combination with the explosion chamber, and a separate ignition chamber, communicating therewith, of a spray box located exteriorly to the said chambers, and provided
10 with a fuel reservoir and separate passages from said reservoir to the said chambers, separate valves controlling said passages, a pump connected with said reservoir, and a governor controlling said pump.
- 15 6. In an internal combustion engine, the combination with the explosion chamber, and a separate ignition chamber, communicating therewith, of a spray box located exteriorly to the said chambers, and provided
20 with a fuel reservoir and separate passages from said reservoir to the said chambers, said box having an annular port surrounding the passage leading to the ignition chamber, said port communicating with said pas-

sage, a fuel supply pump connected with 25 said port, and a governor controlling said pump, separate valves controlling the fuel supply passages to the said chambers, and actuating mechanism for said valves.

7. In an internal combustion engine of the kind referred to, the combination with the device for spraying the charge into the main combustion chamber, and provided with a reservoir for the charge to be sprayed, of a device for spraying the auxiliary charge 35 into the igniter chamber, the reservoir or space for containing the auxiliary charge being so proportioned and arranged that all oil in excess of that required for the auxiliary charge flows into the reservoir of the 40 main spraying device, substantially as described.

Dated this 24th day of February 1909.
